UNITED STATES PATENT OFFICE

140,400

DESIGN FOR A DICKEY

Lilyan Malmstead, Worcester, Mass.

Application October 4, 1944, Serial No. 115,605

Term of patent 14 years

(Cl. D3—25)

To all whom it may concern:

Be it known that I, Lilyan Malmstead, a citizen of the United States and being a resident of Worcester, in the county of Worcester and State of Massachusetts, have invented a new, original, and ornamental Design for a Dickey, of which the following is a specification, reference being had to the accompanying drawing, forming a part thereof.

The figure on the drawing is a front view of a dickey showing my new design.

The back of the dickey is conventionally plain.

I claim:

The ornamental design for a dickey, substantially as shown and described.

LILYAN MALMSTEAD.
